(57) **CLAIM**

The ornamental design for a protective garment, as shown and described.

DESCRIPTION

The patent file contains at least one drawing executed in color. Copies of this patent with color drawings will be provided by the Office upon request and payment of the necessary fee.

FIG. 1 is a top and front perspective view of a protective garment showing our new design according to a first embodiment;

FIG. 2 is a front view thereof;

FIG. 3 is a rear view thereof;

FIG. 4 is a right side view thereof;

FIG. 5 is a left side view thereof;

FIG. 6 is a top and rear perspective view thereof;

FIG. 7 is a top and front perspective view of a protective garment showing our new design according to a second embodiment;

FIG. 8 is a front view thereof;

FIG. 9 is a rear view thereof;

FIG. 10 is a right side view thereof;

FIG. 11 is a left side view thereof; and,

FIG. 12 is a top and rear perspective view thereof.

The short, angled dashed line towards the bottom of the front flap of the protective garment—shown in red in FIGS. 7-8 illustrates stitching that forms part of the claimed design. The remaining dashed broken lines in the figures illustrate portions of the protective garment and environment that form no part of the claimed design.
